* cited by examiner

Primary Examiner — Sandra Snapp*Assistant Examiner* — Ieisha Price(74) *Attorney, Agent, or Firm* — Birch, Stewart, Kolasch & Birch, LLP(57) **CLAIM**

The ornamental design for a wall board attachment lug, as shown and described.

DESCRIPTION

FIG. 1 is a front view of a wall board attachment lug showing my new design;

FIG. 2 is a back view thereof;

FIG. 3 is a top view thereof;

FIG. 4 is a bottom view thereof;

FIG. 5 is a right side view thereof;

FIG. 6 is a left side view thereto; and,

FIG. 7 is a front, right perspective view thereof.

The broken lines in the drawings illustrate portions of the wall board attachment lug and form no part of the claimed design.
